UNITED STATES PATENT OFFICE.

WILLIAM W. LASKER, OF BROOKLYN, NEW YORK, AND JOHN MUELLER, OF NORTH BERGEN, NEW JERSEY, ASSIGNEES, BY MESNE ASSIGNMENTS, TO REMINGTON RAND INC., OF NEW YORK, N. Y., A CORPORATION OF DELAWARE.

TYPE SECTOR.

Application filed June 30, 1925. Serial No. 40,603.

The present invention relates to type carrying sectors for printing mechanisms, such for example as operate through the use of perforated cards as in printing tabulating machines. More specifically the invention relates to a novel alphabetical type sector for positioning the type in printing position in accordance with perforations in a card representing the letter or letters of the alphabet to be printed.

Some of the objects of the present invention are to provide an improved type carrying sector for printing tabulators or any other machines wherein a unit of this character may be applicable; to provide a control for a type sector whereby a maximum number of type are carried by the sector and brought to printing position with a minimum of sector movement; to provide a type sector control whereby type representing all the letters of the alphabet can be set in printing position respectively by twelve control stops; to provide a type sector control consisting of a relatively small number of control members for positioning a relatively large number of type; to provide a type sector control whereby one set of sector control members can be employed to position two groups of type, both groups together forming a complete alphabet; and to provide other improvements as will hereinafter appear.

In the accompanying drawings Fig. 1 represents a side elevation of a type sector control embodying one form of the present invention; and Fig. 2 represents a detail in end elevation of the sector latch mechanism.

Referring to the drawings, one form of the present invention comprises a type sector 10 pivoted to a fixed pivot 11 and carrying a plurality of type 12 which are to be brought into operative relation with a platen 13 about which the paper to receive the impression passes as will be understood. The type printing takes place by the operation of a pivoted hammer 14 striking the positioned type when the hammer latch 15 is released to permit the hammer spring 16 to come into action. The latch 15 is set for releasing by a pivoted latch operating bar 17 which is arranged to be shifted to set position by the rocking movement of a pivoted bell crank 18, the long arm of which extends into the path of a cam 20 on the

sector 10. The hammer release and restoring mechanism comprises a bail 19, a crank arm 21, a shaft 22 on which the bail and crank are fastened, and a retractor link 23, which latter connects to an arm 24 fast to the shaft 25 and which also carries one end 55 of a link 26. The other end of the link 26 is pivoted to an arm 27 which has a rod 28 to engage and return the sector 10 after a printing operation. A spring 30 connects an extension 31 of the sector 10 with a fixed part 32 whereby the spring 30 throws the sector to operative position when it is released. The details of the hammer release and restoring mechanism are referred to more or less generally because they are of 60 the type shown in Patent No. 1,245,502, and have no specific bearing upon the present invention. That is to say, the sector invention herein described might be employed with various other hammer adjuncts and perform 65 as satisfactorily as with those here shown by way of example.

The type 12 are mounted upon the sector 10 which is substantially of quadrant shape so that all of the type can be brought to 70 proper printing position in accordance with the movement of the sector. In the present instance the type have alphabetical characters and the arrangement of them is preferably a group one rather than a consecutive 75 one. Thus one group beginning with the letter A and ending with letter L comprises the even number type, while the other group from letter M to Z comprises the odd number type; for example, beginning with the 80 free end of the sector, the second, fourth, sixth, etc. type carry respectively the characters A, B, C, etc., while the first, third, fifth, etc. type carry respectively the characters M, N, O, etc.

For the purpose of locating the sector 10 so that the selected type is in printing position with respect to the platen 13, a plurality of stop pins 33 are provided and located below but in the plane of movement 95 of a stop lug 34 carried by the sector 10. In the present instance there are eleven pins 33 and one pivoted shutter stop 35, the latter being normally engaged by the lug 34 to hold the sector 10 in its initial non-printing position. The pins 33 are raised into the path of the lug 34 by the action of an analyzing unit operating on a card perfo-

rated in a predetermined manner. The lifting of any one of the pins 33 by the setting action of the analyzing unit causes the shutter stop 35 to swing out of the path of the lug 34 to thus release the sector for swinging movement. The analyzer unit and card control for the pins 33 form no part of the present invention and are therefore not illustrated but they may be of any form 10 known in the art, of which a typical example is shown and described in U. S. Letters Patent No. 1,236,481.

In order to control the sector 10 for the two letter groups, the stop lug 34 projects 15 from a keeper 36 pivoted at 37 to the sector 10 and provided with an offset shoulder 38 arranged to be engaged by a heel latch 40. This latch 40 is pivoted at 41 to the heel of the sector and has stepped latch faces 42 20 and 43 for separately engaging the shoulder 38 according to whether one or the other face is in use as the retaining latch. The other end of the latch 40 is connected by a spring 44 with a hook extension 45 laterally 25 projecting from the keeper 36 so that the latch 40 is yieldably held in latched position. At the opposite end of the keeper 36 there is a lug 46 which serves as a stop to limit the movement of the keeper by abutting 30 a stop pin 47 on the fixed frame 48. With the shoulder 42 of the heel latch 40 in engagement with the off-set shoulder 38 of the keeper 36 as shown in Fig. 1, the type sector will be held in its non-printing position upon forward movement of the rod 28.

The two latch faces 42 and 43 are provided so that the sector 10 can have two fixed initial positions, one for each type group, and by changing from one latch position to 40 the other the group change can be made at will. Thus as shown the latch face 42 is latched over the keeper shoulder 38 and the type sector in the initial but non-printing position of the group beginning with A, but if the latch face 43 is brought into operation 45 the sector will be swung to a new initial position when rod 28 is moved forward and type M will then be in printing position. In other words the distance between the 50 latch face 42 and 43 is the same as the length of the arc between two adjacent type, while the distance between the adjacent pins 33, as well as the distance from the shutter 35 to the next adjacent pin 33 corresponds to 55 the length of the arc between every alternate type or adjacent type of the same group. Thus with the latch face 42 engaging the keeper shoulder 38, the operation of the stop pins 33 will result in the sector 10 taking positions corresponding to the type group beginning with the letter A, and with 60 the latch face 43 engaging the keeper shoulder 38, the operation of the stop pins 33 will result in the sector 10 taking positions cor-

responding to the type group beginning with 65 the letter M.

As a means for automatically changing from the group latch 42 to the group latch 43 according to requirements, a release pin 50 is provided having its upper end below 70 and in close proximity to a part 51 of the latch 40, the arrangement being such that an upward movement of the pin 50, caused by a perforated card indicating a letter in the group beginning with M, will lift the 75 latch 40 against the tension of the spring 44 so that the shoulder 38 will be engaged by the shoulder 43 of the latch 40 as the rod 28 is moved forward. A stop pin 52 serves to prevent undue turning movement of the 80 latch 40 as well as overthrow the keeper 36.

In operation of the control system it is evident that one group of type will require but a single perforation in its proper place on the card to set up a selected type, while 85 for a selected type in the other group, except the first one, two perforations in the card will be necessary and one of these is the same for each type. Thus as here shown 90 a card punched for the letter M in the location to operate the release latch 50 will cause such release latch 50 to change latch 40 from face 42 to face 43 and thereby permit the sector to swing the required distance to bring the M type into position. Since 95 the shutter 35 remains stationary the lug 34 is not released and at the end of the cycle the restoring link 26 brings the sector heel back to relatch the shoulder 38 with the face 42.

Now if type N is to be set up the card 100 will have the perforation necessary to operate release pin 50 plus a perforation in the location necessary to lift the first of the pins 33 and as this latter is raised it shifts the shutter 35 to release the lug 34 of the keeper 36. The pin 50 in the meantime has changed 105 the latch 40 so that its face 43 will be in a position to cooperate with the shoulder 38 and consequently when the sector swings under the pull of the spring 30 until the lug 34 abuts the set pin 33, the N type will be in 110 printing position with respect to the platen 13. When a letter of the other group is to be brought to printing position but one perforation in the proper place in the card is 115 necessary, and since the release pin 50 is not caused to function, the latch face 42 will control the position of the sector and allow 120 it to bring alternate type to printing position.

It will now be apparent that a complete unitary sector for alphabetical printing has been devised wherein the number of parts usually believed necessary to carry out the desired function has been materially reduced, while in place of a multi-part sector a single integral element has been devised and a control therefor provided which is 125

positive in action, rugged in construction and accurate in operation. Furthermore the construction provides for at least twenty-three type positions and control for them by a minimum of set-up pins controlled from a card analyzing unit.

While only a single form is shown in which this invention may be embodied, it is to be understood that the invention is not limited to any specific construction, but might be applied to various forms without departing from the spirit of the invention or the scope of the appended claims.

Having thus described our invention, we claim:

1. In a machine of the printing tabulator type operated by a perforated card, a platen, a type sector arranged to swing into operative relation to said platen, two groups of type carried by said sector, a plurality of stop pins less in number than the number of type arranged to be operated in accordance with the perforations in a card, a lug adjustably carried by said sector and located to intercept any set stop pin, means engaging said lug to hold said sector in an initial position, and means for changing the relation between said lug and said sector to vary the initial position of said sector whereby the printing position of said type is changed from one group to another.

2. In a machine of the printing tabulator type operated by a perforated card, a platen, a type sector arranged to swing into operative relation to said platen, two groups of type carried by said sector, a plurality of stop pins less in number than the number of type arranged to be operated in accordance with the perforations in a card, a lug pivoted to said sector and located to intercept any set stop pin, means engaging said lug to hold said sector in an initial position, and means for changing the relation between said lug and said sector, to vary the initial position of said sector whereby the printing position of said type is changed from one group to the other.

3. In a machine of the printing tabulator type operated by a perforated card, a platen, a type sector arranged to swing into operative relation to said platen, two groups of type carried by said sector, a plurality of stop pins less in number than the number of type arranged to be operated in accordance with the perforations in a card, a lug pivoted to said sector and located to intercept any set stop pin, means engaging said lug to hold said sector in an initial position, and means including a latch pivoted to said sector for changing the relation between said lug and said sector to vary the initial position of said sector, whereby the printing position of said type is changed from one group to the other.

4. In a machine of the printing tabulator

type operated by a perforated card, a platen, a type sector arranged to swing into operative relation to said platen, two groups of type carried by said sector, a plurality of stop pins less in number than the number of type arranged to be operated in accordance with the perforations in a card, a lug pivoted to said sector and located to intercept any set stop pin, means engaging said lug to hold said sector in an initial position, and means including a latch having two latching faces and pivoted to said sector for changing the relation between said lug and said sector to vary the initial position of said sector, whereby the printing position of said type is changed from one group to the other.

5. In a machine of the printing tabulator type operated by a perforated card, a platen, a type sector arranged to swing into operative relation to said platen, two groups of type carried by said sector, a plurality of stop pins less in number than the number of type arranged to be operated in accordance with the perforations in a card, a lug pivoted to said sector and located to intercept any set stop pin, means engaging said lug to hold said sector in an initial position, means for changing the relation between said lug and said sector to vary the initial position of said sector whereby the printing position of said type is changed from one group to the other, and means controlled by a perforated card for releasing said lug.

6. In a machine of the printing tabulator type operated by a perforated card, a platen, a type sector arranged to swing into operative relation to said platen, two groups of type carried by said sector, a plurality of stop pins less in number than the number of type arranged to be operated in accordance with the perforations in a card, a lug pivoted to said sector and located to intercept any set stop pin, means engaging said lug, means including a latch pivoted to said sector for changing the relation between said lug and said sector to vary the initial position of said sector whereby the printing position of said type is changed from one group to the other, and means controlled by a perforated card for automatically operating said latch.

7. In a machine of the printing tabulator type operated by a perforated card, a platen, a type sector arranged to swing into operative relation to said platen, two groups of type carried by said sector, a plurality of stop pins less in number than the number of type arranged to be operated in accordance with the perforations in a card, a lug pivoted to said sector and located to intercept any set stop pin, means engaging said lug to hold said sector in an initial position, means including a latch having two latching faces and pivoted to said sector for changing the relation between said lug and said sector

to vary the initial position of said sector, whereby the printing position of said type is changed from one group to the other, and means controlled by a perforated card for shifting said latch from one latch face to the other, whereby the type groups are changed from one to the other.

8. In a machine of the class described, the combination of a differentially movable member, a series of stops to limit the differential movement of said member, and

stop cooperating means mounted on said member and adjustable into a plurality of positions on said member for limiting the movement of said member in one of a plurality of positions for each of said stops. 15
